UNITED STATES PATENT OFFICE.

CARL WINKLER, OF BERNE, SWITZERLAND.

MOLD FOR STEREOTYPE-PLATES AND THE LIKE.

1,313,774.

Specification of Letters Patent.

Patented Aug. 19, 1919.

Application filed July 26, 1918. Serial No. 111,488.

To all whom it may concern:

Be it known that I, CARL WINKLER, a citizen of the Swiss Republic, residing at Berne, in the Swiss Republic, have invented new and useful Improvements in Molds for Stereotype-Plates and the like, of which the following is a specification.

My present invention relates to a mold for casting stereotype plates and the like, in which said plates, when cast, are cooled in a special manner. The object of my invention is to produce a plate which will answer the strictest requirements in regard to accuracy, and, consequently, can be used, with the best results, for color printing.

On the drawing two constructions of the new mold are shown:

Figure 1 being a cross section through a mold in which a special vessel for containing the cooling water is provided in the drag.

Fig. 2 is an elevation of the mold as seen in the direction of the arrow shown in Fig. 1.

Fig. 3 shows a cross section, corresponding to Fig. 1, of a second construction.

Fig. 4 is an elevation, corresponding to Fig. 2, of the mold shown in Fig. 3.

In existing constructions of molds used for casting stereotype plates, and the like, in which the cooling is effected by means of chambers provided in the parts of the mold, it is a great drawback that the cooling agent used (water, steam, or the like) penetrates through the walls of said chambers and badly influences the casting process.

According to my present invention this drawback is overcome by carrying out the cooling process indirectly, instead of directly, as heretofore. For example, as shown in Figs. 1 and 2, a vessel *c*, adapted to contain the cooling agent, is placed against the inner wall of the drag *a*, which is arranged in known manner in regard to the bed *b*. The cooling agent is fed to the vessel *c* through the pipe *d* at one end, and it is led off at the other end by a pipe *e*. The feed pipe *d* extends over the entire length of the vessel *c*, and inside said vessel, it has a number of small perforations, through which the cooling agent escapes, in order to run down the wall of said vessel, and to collect therein.

The bed *b* may either be cooled directly by feeding the cooling agent direct into the mantle *f*, or, as in the case of the drag, by

providing a special vessel for the cooling agent.

As, in such molds, the temperature near the inlet for the molten metal is much higher than on the opposite side, it is of advantage to make the wall of the mold, near to said inlet, or at other points where the temperature is higher, thinner than at other parts so that the cooling effect exercised at such thinner parts is correspondingly greater, and consequently, a uniform temperature is approached throughout the whole mold. Such an arrangement is shown, by way of example, in Figs. 3 and 4. The vessel *c'*, adapted to contain the cooling agent, is arranged in the cooling chamber of the drag *a'* in such a manner that it bears against the wall of said drag, and this wall is thinner near the inlet *g'* for the molten metal than at other parts, so that the vessel is eccentric to the mold.

Instead of making a special vessel *c*, *c'* and inserting said vessel in the cooling chamber of the drag and bed, it suffices to provide the inside walls of the cooling chamber with a metal deposit which will close the pores in said walls. Experiments have shown that for this purpose, for example, the metal spraying process may be used with advantage, although an electrolytic, or other, deposit of copper, tin, zinc, or other metal, may also be used.

What I claim and desire to secure by Letters Patent is:—

1. The combination with a mold for stereotype plates, and the like, having cooling chambers in the parts thereof, of means to prevent the cooling agent used from coming into immediate contact with the walls of said cooling chambers, substantially as, and for the purpose, set forth.

2. The combination with a mold for stereotype plates, and the like, having cooling chambers in the parts thereof, of a metal layer protecting the walls of said cooling chambers from contact with the cooling agent, substantially as, and for the purpose, set forth.

In testimony whereof I have signed my name to this specification in the presence of two subscribing witnesses.

CARL WINKLER.
